FIG. 3.

UNITED STATES PATENT OFFICE

JOSEPH CHARLES BENNETT, OF TORONTO, ONTARIO, CANADA, ASSIGNOR TO OTIS-FENSOM ELEVATOR COMPANY, LIMITED, OF TORONTO, CANADA.

ELEVATOR-GATE.

1,156,204.

Specification of Letters Patent. Patented Oct. 12, 1915.

Application filed April 24, 1915. Serial No. 23,592.

To all whom it may concern:

Be it known that I, JOSEPH CHARLES BENNETT, of the city of Toronto, in the county of York, in the Province of Ontario, Canada, have invented certain new and useful Improvements in Elevator-Gates, of which the following is the specification.

My invention relates to improvements in elevator gates and the object of the invention is to devise a gate which will collapse vertically in order to give sufficient head room beneath the gate when the gate is raised to the open position in buildings constructed with low ceilings and it consists essentially of an elevator gate comprising a plurality of bar members slidably held at their ends in vertical guides, a counter-weight support for the gate connected to the center bar member and a criss-cross link connection between the bars of the gate adapted to draw the bars together when the gate is raised and to hold them in a definite parallel position one to the other as hereinafter more particularly explained by the following specification.

Figure 1, is a front elevation of my gate shown in the closed position and the usual guides therefor. Fig. 2, is a similar view to Fig. 1 showing the gate in the open position. Fig. 3, is a sectional plan view on line *x—y* Fig. 1.

In the drawings like letters of reference indicate corresponding parts in each figure. 1 and 2 indicate the side posts located at each side of the elevator shaft and forming the door opening.

3 indicates the floor level and 4 the ceiling level.

5 and 6 indicate guiding bars and 7, 7 indicate inwardly extending portions formed integral with each upper end of the guiding bars and forming stops for the elevator gate when it is raised to the open position.

8, 8 indicate pulleys journaled at the upper ends of the side posts 1 and 2.

9 indicate cords extending over the pulleys 8 opposite the ends of the cords being provided with suitable counterweights which are not shown as these are commonly employed in all elevator gates of this type.

10 indicates the elevator gate comprising the main cross-bars 11, 12 and 13.

14, 14 indicate guideways secured to the

ends of the bar members 11, 12 and 13 and formed substantially U-shaped in section so as to extend to each side of the bars 5 and 6.

15 and 16 indicate slots formed in the bar member 11 and extending longitudinally thereof and located in proximity to each end of the bar member.

17 indicates a similar slot located intermediate of the length of the bar member 11.

18 and 19 indicate slots formed in the bar member 12 similar to the slots 15 and 16.

20 and 21 indicate slots formed in the bar member 13 and also similar to the slots 15 and 16. The slots 16, 19 and 21 are arranged in vertical alinement and the slots 15, 18 and 20 are also arranged in vertical alinement.

22 indicates a slot formed in the bar member 13 in horizontal alinement with the slots 20 and 21 and located intermediate of the length of the bar member between the slots 20 and 21.

23 and 24 indicate slots formed in the bar member 12 in horizontal alinement with the slots 18 and 19, the slots 23 and 24 being located at each side of the center of the bar member 12.

25 indicates a lever bar.

26 indicates a bolt on which the lever bar 25 is swung. The bolt 26 extends through the slot 17 and is freely secured therein by a nut 28 so as to permit of free movement of the bolt longitudinally within the slot. 29 indicates a similar lever bar member.

30 indicates a bolt extending centrally through the lever bar member 29 and 90 through the slot 22, the opposite end being also provided with a nut similar to the nut 28 hereinbefore referred to allowing free movement of the bolt 30 longitudinally of the slot 22.

31 indicates a bar member located intermediate between the main bar members 11 and 12. 32 indicates a similar bar member located between the main bar members 12 and 13.

33 and 34 indicate cross link members pivotally secured to the bar 32 by a bolt 35. The lower end of the link bar member 34 is pivotally connected to one end of the lever bar 29. The lower end of the link bar 33 is connected to the main bar member 13 by

a bolt 36 extending freely through the slot 21.

37 indicates a link bar pivotally connected at its lower end to the upper end of the link bar 33 and at its upper end to one end of the lever bar 25. The link bar 37 is pivotally secured intermediately of its length to the bar member 31 by a bolt 37^x.

38 indicates a link bar swung on the bolt 37^x at its upper end and pivotally connected at its lower end to the upper end of the link bar 34 by a bolt 38^x extending freely through the slot 18 of the main bar member 12.

39 and 40 indicate cross links pivotally connected together and to the bar 31 by a bolt 41. The upper end of the link bar 40 is pivotally connected to the opposite end of the lever 25. The upper end of the link bar 39 is connected to the main bar member 11 by a bolt 39^x extending freely through the slot 16.

42 indicates a link bar pivotally connected intermediately of its length by a bolt 42^x to the bar 32. The upper end of the link bar 42 is pivotally connected to the link bar 39 by a bolt 43, the bolt 43 extending freely through the slot 24. The lower end of the link bar 42 is pivotally connected to the opposite end of the lever bar 29.

44 is a link bar swung at its lower end upon the bolt 42^x and pivotally connected at its upper end by a bolt 45 to the lower end of the link bar 40, the bolt 45 extending freely through the slot 19 of the main bar member 12.

Having described the principal parts involved in my invention I will briefly describe the operation of the same. It will be understood that according to regulations in force controlling the construction of elevator gates that the height of the gate must be constructed a definite height in compliance with such regulations. In buildings constructed with low ceilings it is impossible to raise the gate to the required height sufficiently to allow head room beneath the gate when the gate is raised. In order to overcome this defect and at the same time comply with the regulations in force I have constructed my gate so that when raised into position in proximity to the ceiling it will automatically collapse into the position shown in Fig. 2 of the drawings. When operating the device the gate is thrown upward by the hand of a person in proximity thereto. The gate flies up until the upper main bar 11 strikes the stops 7. The counterweights descending in the usual manner draw upon the cords 9 giving an upward movement to the bar 12 so that immediately the bar 11 is brought to rest by contact with the stops 7 the bar member 12 is carried upwardly toward the bar member 11 collapsing the links 37, 38, 39 and 40. These links adjust them-

selves in the slots 15, 16, 17, 18, 19, 23 and 24 so as to spread the upper ends of the links 33 and 34, 42 and 44 and thereby draw the bar member 13 upwardly toward the bar member 12 thereby drawing the gate into the collapsed position shown in Fig. 2. It will also be seen that by constructing my device as above described that the bar members 11, 12 and 13 will be always held in a definite parallel position one to the other no matter whether the gate is thrown up by applying the hand to the center portion of the gate or to either of the end portions and thereby will prevent any liability of the gate to bind or jam in its guides when thrown upwardly to the collapsed position.

What I claim as my invention is—

1. In an elevator gate, the combination with the side guides having a suitable stop at the top thereof, of a gate comprising a plurality of parallel main bars having longitudinal slots therein, intermediate bars located alternately between the aforesaid bars, a set of crossed links located at each side of the gate and pivotally connected to each intermediate bar at each end, bolts extending through the ends of the cross links and through the slots of the main bars, means independent of the bars of the gate for connecting the upper end of each set of crossed links together and the lower end of each set of crossed links together, and counterweighted cords connected to the center bar of the gate.

2. In an elevator gate, the combination with the side guides having a suitable stop at the top thereof, of a gate comprising a plurality of parallel main bars having longitudinal slots therein, intermediate bars located alternately between the aforesaid bars, a set of cross links located at each side of the gate and pivotally connected to each intermediate bar, bolts extending through the ends of the cross links and through the slots of the main bars, and lever bars pivotally carried by the top and bottom bars of the gate for connecting the upper end of each set of cross links together and the lower end of each set of cross links together, and counterweighted cords located at each side of the gate and connected to the center bar of the gate.

3. In an elevator gate, the combination with the side guides having a stop at the upper end thereof, of an elevator gate comprising a plurality of main bars slidably supported on the side guides, the upper and lower bar of which is provided with longitudinal slots in proximity to each end thereof, and a longitudinal slot located intermediately of the length thereof and the center bar with longitudinal slots in proximity to each end thereof, and a pair of longitudinal slots located at each side of the center of the bar, lever bars, bolts extending through the lever

bars, and center slot of the upper and lower main bars, intermediate cross bars located alternately between the main bars, a series of cross links connected to the ends of the 5 lever bars and pivotally connected intermediate of their length to the intermediate bars, and bolts extending through the ends

of the cross links and the slots of the main bars and a counterweighted cord connected to the center main bar of the gate.

JOSEPH CHARLES BENNETT.
